UNITED STATES PATENT OFFICE.

RAYMOND B. GILCHRIST, OF NEWARK, NEW JERSEY.

BOTTLE-HOLDER.

No. 823,678.

Specification of Letters Patent.

Patented June 19, 1906.

Application filed March 3, 1905. Serial No. 248,220.

To all whom it may concern:

Be it known that I, RAYMOND B. GILCHRIST, a resident of Newark, in the county of Essex and State of New Jersey, have invented certain new and useful Improvements in Bottle-Holders, of which the following is a full, clear, and exact description.

The invention relates to bottle-holders for cork-pullers, corking-machines, and the like. The invention designs to provide an improved device which is simple in construction, and one feature of the invention consists in an improved construction of bottle-holder in which the jaws have pivots relatively eccentric with respect to each other and are connected to each other by a pin extending through both of the jaws to connect them for simultaneous and equidistant shift.

Another feature of the invention consists in a staple the arms of which form the pivots for the jaws and which provides a detachable connection between the machine-frame and the holder desirable in transportation or when it is desired to operate the machine without the bottle-holder.

In the drawings, Figure 1 is a side elevation of a cork-puller having the improved bottle-holder applied thereto. Fig. 2 is an inverted plan. Fig. 3 is a section on line 3-3 of Fig. 2. Figs. 4 and 5 are detail perspectives of the jaws. Fig. 6 is a detail perspective of the staple. Fig. 7 is a detail of one of the cotter-pins for holding the staple. The bottle-holder comprises a pair of jaws A and A', each of which is provided with an operating-handle a, an elastic liner a', adapted to be forced against the bottle-neck, a hook a'' for engaging the frame to which the bottle-holder will be applied and whereby the free end of the jaw will be held against vertical movement, and a seat a''' for a spring B, whereby the jaws will be pressed into open or spread position. A staple C comprises arms c and c', which form relatively eccentric pivots for the jaws respectively and are each adapted to extend through a hole a⁴ in one of the jaws at one end thereof. The said arms are also adapted to extend through perforations d, formed in an extension or web of the machine-frame D and removably secured in said frame by cotter-pins e. The jaws are connected for equidistant and simultaneous shift by a connecting-pin F, which is adapted to extend through 55 perforations in laterally-projecting lugs a⁵ of

jaw A and through a perforation in a projecting lug a⁶ of jaw A. Lugs a⁵ and a⁶ are arranged to overlap each other and lug a⁶ is preferably arranged to be held between lugs a⁵. Pin F is usually provided with a head f at one end and the other end may be slightly upset, so all danger of separation of the pin from the jaws in packing or transportation is avoided. The pin is loosely held in the perforated lugs, so as to permit the pivotal movement of the jaws about their respective pivots. The pin plays adjacent a line extending through the pin-pivots, and therefore a very slight play suffices to permit pivotal movement of the jaws about their respective pivots.

In Fig. 1 the bottle-holder is shown as applied to the frame D of a cork-puller to hold a bottle beneath the corkscrew during operation of the puller. It will be understood that the improved bottle-holder may be applied to other machines, such as corking-machines and the like.

An important advantage of the improved construction is that upon withdrawal of the staple from the perforations in the frame, which can be done upon removal of cotter-pins e from the arms of the staple, the bottle-holder can be conveniently removed from the machine-frame when use of the bottle-holder is not desired or when the machine is packed for shipment, because a much larger packing-case is necessary for the machine if the bottle-holder, with its laterally-projecting handles, remained attached to the machine. The staple forms a convenient device for attaching and detaching the bottle-holder to the machine-frame and connecting-pin F and connects the jaws to each other, which is also convenient in shipment. The construction of the bottle-holder parts and pivots is such that they can be quickly connected to and disconnected from the frame, and when disconnected the cotter-pins can be again placed into position in staple-arms c and c', and the whole of the bottle-holder will be conveniently held together, so there is no possibility of displacement of the parts.

Having thus described the invention, what I claim as new, and desire to secure by Letters Patent, is—

1. A bottle-holder comprising the combination of a pair of jaws, pivots relatively eccentric with respect to each other, for the jaws respectively, and a pin extending through

both of the jaws and whereby the jaws will be pivotally connected to each other and simultaneously and equidistantly shifted, substantially as described.

5. 2. A bottle-holder comprising the combination of a pair of jaws relatively eccentric pivots for the jaws respectively, overlapping perforated lugs on the jaws respectively, and a pin extending through the perforations and 10 pivotally connecting the jaws to each other, substantially as described.

3. A bottle-holder comprising the combination of a support a pair of jaws having perforations therein, and a staple having arms extending through said perforations forming relatively eccentric pivots for the jaws respectively and removably held in said support, substantially as described.

4. A bottle-holder comprising the combination of a pair of jaws, a staple having arms forming relatively eccentric pivots for the jaws respectively, and a pin whereby the 20

jaws are pivotally connected to each other, substantially as described.

5. A bottle-holder comprising the combination of a frame a pair of jaws, a staple having arms forming relatively eccentric pivots for the jaws respectively, adapted to pass through perforations in the frame, and having their ends perforated, and pins adapted 30 to pass through said perforations to removably secure the bottle-holder and frame in connected relation, substantially as described.

6. The combination with a frame of a bottle-holder comprising a pair of jaws, a staple having arms forming relatively eccentric pivots for the jaws respectively, a pin pivotally connecting the jaws to each other, and means for removably securing the staple in the frame, substantially as described.

RAYMOND B. GILCHRIST.
